United States Patent Office

Des. 187,669
Patented Apr. 12, 1960

187,669

COMBINED THERMOMETER AND HYGROMETER

Wallace A. Monson, St. Paul, Minn., assignor to Brown & Bigelow, St. Paul, Minn., a corporation of Minnesota

Application December 12, 1958, Serial No. 53,750

Term of patent 7 years

(Cl. D52—7)

FIG. 1

FIG. 2

FIG. 3

Fig. 1 is a perspective view of a combined thermometer and hygrometer, showing my new design;

Fig. 2 is a rear plan view thereof, with the instrument resting on its front face; and

Fig. 3 is a side elevational view thereof.

I claim:

The ornamental design for a combined thermometer and hygrometer, as shown.
